UNITED STATES PATENT OFFICE.

EDWARD D. TIFFANY, OF ALBION, NEW YORK, ASSIGNOR OF ONE-HALF TO JAMES DE PLANTY, OF ALBION, NEW YORK.

CLAM-OPENER.

1,041,198.

Specification of Letters Patent.

Patented Oct. 15, 1912.

Application filed January 23, 1912. Serial No. 672,918.

To all whom it may concern:

Be it known that I, EDWARD D. TIFFANY, a citizen of the United States, residing at Albion, in the county of Orleans and State 5 of New York, have invented certain new and useful Improvements in Clam-Openers, of which the following is a specification, reference being had therein to the accompanying drawing.

10 This invention relates to clam openers and has special reference to a clam opening device having clamping means for holding the clam when the same is being opened.

The principal object of the invention is to 15 improve the general construction of devices of this character.

Another object of this invention is to provide improved means for holding the clam in position.

20 A third object of the invention is to provide means for permitting the clam juice to flow in a predetermined direction so that the same can be collected.

With the above and other objects in view 25 the invention consists in general of certain novel details of construction, arrangements and combination of parts as will be herein-after fully described and illustrated.

In the accompanying drawings, like characters of reference indicate like parts in the 30 several views, and Figure 1 is a side elevation of the improved opener constructed in accordance with this invention. Fig. 2 is a similar view taken from the opposite side 35 and showing the device in position after the shell of the clam has been split. Fig. 3 is a front elevation of the device. Fig. 4 is a bottom plan view of the device. Fig. 5 is a detail perspective of a certain spring tong 40 used for engaging clam shells. Fig. 6 is a view of a certain pawl used in tilting the lower jaw of the clamp so as to pour the clam juice forwardly off the jaw. Fig. 7 is a detail perspective of a certain pawl used 45 in holding the tray in a level position.

This invention has at its front end a pair 50 of spaced standards 10 which rest on feet 11. These standards are held in position at their upper ends by a cross bar 12. Attached to each of the standards intermediate its height 55 is a frame bar 13 and these bars are bent in at the rear to lie in close proximity as at 14. Between the rear ends of the bars 13 is a rear leg or standard 15 which is supported on a foot 16. Screw holes may be made in

one or more of the feet 11 and 16, but in the present instance one screw hole is shown in the foot 16 as at 17, as this has been found to be all that was necessary to hold the device in position on a table or bench. Pivotally mounted on the cross bar 12 is an operating lever 18 provided with a handle 19. Between the ends 14 of the frame bars is a pair of spaced standards 20 which are firmly secured to the frame bars. These standards are formed from a single strip of metal bent at its middle and having the parts adjacent the bend in contact while the ends are spaced to form a species of substantially Y-shaped structure. Between the upper ends of these 60 spaced standards is pivoted the rear end of a knife 21, the forward end of which extends between the standards 10. Intermediate the ends of the lever 18 and the knife 21 the lever and knife are connected by means of pivoted links 22. In order to hold the knife normally in a raised position at its forward end a coil spring surrounds the bar 12 as indicated at 23 and the intermediate portion of this spring passes beneath the lever 65 18 as at 24 so that, the ends of the spring being hooked around the standards 10, this spring will constantly tend to raise the lever 18 and with it the knife. Extending between the forward ends of the frame bars 13 is a shaft 25 whereon rocks a tray 26 which is shaped to correspond to the shape of the space between the forward portions of the frame bars 13 and has its upper sides and rear portion surrounded by a rim 27. Extending longitudinally of a certain portion of this frame bar is a grooved rib 28 which receives the edge of the clam to be opened. Pivoted on the bolt 29 which secures the 70 knife 21 to the standards 20 is an upper clamping member which consists of a piece of resilient material bent intermediate its ends as at 30 so that the two portions lie in close proximity. Forward of these two 75 portions the arms of this member are separated as at 31 to lie on opposite sides of the standards 20. These arms are also curved outwardly and inwardly as at 32 for the purpose of permitting the passage between them of the links 22. On the forward ends of these arms is carried a pair of co-acting clamping members 33 which, when together, 80 present a surface somewhat spoon shaped in form so that the sides of the clam shell are clasped therebetween. These members 85 90 95 100 105 110

are separated slightly and their proximal surfaces form a somewhat wedge-shaped groove so that the knife may pass readily between them.

5 Between the rear end 30 of this spring clamp and the frame members 13 is a compression spring 34 which normally tends to force the members 33 toward the tray 26. Surrounding the bar 25 is a coil spring 35 10 the middle part of which is unwound to form a bight portion 36 which depends against the forward portion of the underside of the tray 26. The ends of the spring 35 are engaged beneath the frame bars 13 15 as indicated at 37. For the purpose of utilizing the tray 26 so that its front end dips downward to empty clam juice into a convenient receptacle there is provided a pawl 38 which has its upper end pivoted to the lever 18 and its lower end provided with 20 a notch 39 for engagement beneath the end of the tray, an angled extremity 40 being provided so that it may ride over the end of the tray 26 during the downward movement of the lever. A spring 41 is secured 25 to the lever and pawl at its opposite end and normally tends to draw the pawl upward so that the notch will engage the rear end of the tray when the same is forced downwardly.

30 For the purpose of holding the tray in position during the opening of the clam there is provided a pawl 42 which is mounted on a pin 43 soldered or otherwise secured 35 beneath the frame bars 13. This pawl 42 likewise has a notch 44 at its point of extremity 45. Furthermore, the pawl carries just back of the notch a projecting pin 46. This pawl normally has its upper end urged 40 forward by means of a spring 47 attached to the lower end of the pawl at one end and to one of the frame bars 13 at its opposite end.

45 In the operation of the device the tray is brought to its level position and in this position the notch 44 will engage the rear end of the tray. The clam is then forced in on the tray with the members 33 grasping the upper portion and the lower edge 50 of the shell resting in the groove of the rib 28. The handle 19 is then depressed. This forces the knife 21 downward at its forward end and the knife passes between the members 33 entering the crack between the 55 edges of the clam shell, thus separating the shell. At the same time the end 40 of the pawl 38 strikes the pin 46 and forces the upper end of the pawl 42 backward against the tension of the spring 47. This releases 60 the tray from the notch 44 and, at the same time, the lower end of the pawl 38 is forced back against the tension of the spring 41 until the notch 39 engages the rear end of the tray. Upon the release of the handle 65 19 the tray will be tilted upward to a cer-

tain point thus permitting the juice to flow forward where it may be caught in a suitable cup, or other receptacle. The clam may then be removed from between the clamps and the handle permitted to rise still farther 70 and as the handle rises still farther the pawl 38 will slip off the tray whereby the spring 35 will act to restore the tray to its position, the rear end of the tray forcing the upper end of the pawl backward so that this rear 75 end is again engaged by the notch 44. It is obvious that the operation may be repeated as often as necessary.

There has thus been provided a simple and efficient device of the kind described 80 and for the purpose specified.

Having thus described the invention, what is claimed as new, is:—

1. In a clam opener, a frame, a tilting frame constituting a tray, a clamp, a second 85 clamp co-operating with the first mentioned clamp and consisting of a pair of co-acting members, a knife adapted to move between the members of the second clamp, and means to move said knife.

2. In a clam opener, a frame, a tilting clamp constituting a tray pivoted on said frame, means normally holding said clamp in a horizontal position, means to tilt said clamp, a second clamp co-acting with the 95 first clamp, and a knife for opening a clam held between said clamps.

3. In a clam opener, a frame, a lower clamp mounted on said frame, an upper clamp consisting of a pair of co-acting members having cymbiform proximal surfaces, a pivoted knife mounted to swing between the members of the upper clamp, an operating lever pivoted to said frame, and links connecting said knife and operating lever.

4. A clam opener, a frame, a tilting lower clamp pivotally mounted on said frame and consisting of a tray, a pawl pivoted on said frame and normally engaging the rear end of said tray to hold the same in a horizontal position, a pawl having a notched end, a spring urging the notched end of said pawl into engagement with said tray, a pin projecting laterally from the pawl adjacent the notch, an operating lever pivotally mounted on said frame, a second pawl pivoted to the operating lever and provided with a pointed end having a notch adjacent thereto, said pointed end being adapted to engage the pin and rear end of the tray as the second pawl 110 is forced downward, and a spring normally urging the lower end of said second pawl forward.

5. In a clam opener, a frame, a standard carried by said frame, a strip of resilient 125 metal bent centrally to provide arms, one on each side of said standard, a pair of co-acting clamping jaws, each carried on one of said arms, a spring normally urging said clamping jaws downward, a knife pivoted 130

- to said standard to pass between said clamping jaws, an operating lever, a link connecting said lever and knife, and a second clamp coöoperating with said pair of clamping jaws.
- 5 6. In a clam opener, a frame, a standard carried by said frame, a strip of resilient metal bent centrally to provide arms, one on each side of said standard, a pair of co-acting clamping jaws, each carried on one of
- 10 said arms, a spring normally urging said clamping jaws downward, a knife pivoted to said standard to pass between said clamping jaws, an operating lever, a link connecting said lever and knife, a second clamp coöoperating with said clamping jaws pivot-
- 15 ally mounted on said frame, means normally holding said third clamp in horizontal position, and means connected to said lever for tilting said second clamp.
- 20 7. In a clam opener, a frame, a standard carried by said frame, a strip of resilient

metal bent centrally to provide arms, one on each side of said standard, a pair of co-acting clamping jaws, each carried on one of said arms, a spring normally urging said 25 clamping jaws downward, a knife pivoted to said standard to pass between said clamping jaws, an operating lever, a link connecting said lever and knife, a second clamp coöoperating with said clamping jaws pivot- 30 ally mounted on said frame, means normally holding said second clamp in horizontal position, and means connected to said lever for tilting said second clamp, and a spring for returning the second clamp to horizontal 35 position when tilted.

In testimony whereof I hereunto affix my signature in presence of two witnesses.

EDWARD D. TIFFANY.
